UNITED STATES PATENT OFFICE.

RICHARD P. BOONE, OF KIRKERSVILLE, OHIO.

RACK.

1,237,997.

Specification of Letters Patent. Patented Aug. 21, 1917.

Application filed January 19, 1917. Serial No. 143,321.

To all whom it may concern:

Be it known that I, RICHARD P. BOONE, a citizen of the United States, and a resident of Kirkersville, in the county of Licking 5 and State of Ohio, have invented a new and useful Rack, of which the following is a specification.

My invention relates particularly to portable racks on which clothes may be hung to 10 dry.

The principal object of the invention is to generally improve the construction and to increase the utility and efficiency of devices of this character. The particular nature of 15 the improvements, together with their purposes and the advantages accruing from their employment, will be fully described later herein.

The nature of the invention is such that 20 it will be readily understood by reference to the accompanying drawings and the following description, but it must be understood that the drawings show and the description sets forth only that particular embodiment 25 which I at present prefer, and that the details are subject to much modification without departing from the principles and novel features of the invention defined in the appended claim. In said drawings:

30 Figure 1 is an elevation, showing by full lines a preferred embodiment of my invention as in use, and showing by dotted lines the supporting-arms in folded position;

Fig. 2, a sectional detail of the supporting 35 members and parts connected thereto;

Fig. 3, an enlarged plan view of the fixed bracket;

Fig. 4, a similar view of the sliding bracket;

40 Fig. 5, a perspective detail of the thimble;

Fig. 6, a perspective detail of the cap for the socket;

Fig. 7, a perspective detail of the connector; and

45 Fig. 8, a fragmental detail of one of the supporting-arms, showing the manner of engaging a line therewith.

Considering the drawings in detail, 2 indicates a tubular socket adapted to be in 50 serted in a bed 3 of earth, cement, or the like, and 4 indicates a cap-like foot threaded onto its lower end to prevent water accumulating therein.

5 represents a supporting standard, preferably tubular, seated on the foot 4, rotatable within the socket 2, and removable

therefrom. Suitably secured on its lower end, by welding, sweating, pressing, or otherwise, is a rain-excluding thimble 6 having an annular flange 7. 8 denotes a connector the upper end of which fits snugly but slidably and rotatably over the body of the thimble 6 and the lower end of which is threaded onto the upper end of the socket 2, whereby its internal annular shoulder 9 is 65 drawn down tightly upon the thimble-flange 7, and as the latter is thus drawn down firmly upon the upper end of the socket, no rain or other liquid can run into the upper end of the latter. In order to prevent liquids, dirt, etc., entering the socket when the support 5 is removed I provide a screw-cap 10 which is secured by a loop 11 and chain 12 to the socket and which may be threaded thereonto. 75

13 (Figs. 1 and 4) denotes a sliding bracket having a centrally arranged eye 14 from which project radially arranged bracket-arms in pairs 15. A set-screw 16 passes transversely through an aperture in 80 the eye and may be brought to bear against the support 5 to lock said bracket at a selective height thereon.

17 (Figs. 1 and 3) indicates stationary bracket rotatably mounted on the support 5 85 and seated on a collar 18 secured to said support as by a rivet 18'. It comprises a centrally arranged eye 19 from which radiate bracket arms in pairs 20.

A cap 21, serving to prevent water or 90 other matter from entering the support 5, is threaded onto its upper end.

Between each pair 15 of bracket-arms is pivoted the inner end of a line-supporting arm 22, as shown at 23, Fig. 1. Between 95 each pair 20 of bracket-arms is pivoted one end of a link 24 the other end of which is pivoted at 25 to the corresponding arm 22.

In order that the lines 26, which are strung upon the arms 22, may be readily positioned 100 and with equal facility be removed, I provide each arm with transversely arranged eyes 27 each of which communicates with an obliquely arranged slot 28. Each line is passed down through the proper slots, thence 105 drawn into the communicating eyes, and its ends then secured.

It will be clear that when not in use the arms 22 and 24 may be folded to the position indicated by dotted lines in Fig. 1, this being accomplished by loosening the set-screw 110 16 and sliding the bracket 13 downward on

the support 5. Also it will be evident that said support and all parts supported thereby may be removed from the socket 2 and taken to an unexposed position. The rack may be manipulated with but a minimum of effort, for without moving from his position the operator may rotate the rack to bring the different sides thereof within easy access, and it is but a step from a position midway of either arm 22 to any line strung thereon. A suitable socket may be provided for use in a room, and as the capacity of the several lines is very great relatively to the square feet of space occupied thereby, a large washing may be accommodated in an ordinary sized room. When in the open, a breeze will cause the rack to rotate, whereby all of the clothes will at some time be exposed to the direct action of the air currents and they will dry much more rapidly than they would if hung on a stationary rack.

Having thus set forth the nature of the invention I claim as new the following, to-wit:—

In testimony whereof I hereunto set my hand this 8th day of January, 1917, at Newark, county of Licking, State of Ohio.

RICHARD P. BOONE.

Copies of this patent may be obtained for five cents each, by addressing the "Commissioner of Patents, Washington, D. C."
